UNITED STATES PATENT OFFICE

134,728

DESIGN FOR A BOOK MATCH PACKET

Garnet J. Weigel, San Francisco, Calif.

Application April 6, 1942, Serial No. 106,464

Term of patent 3½ years

To all whom it may concern:

Be it known that I, Garnet J. Weigel, a citizen of the United States, residing at the city and county of San Francisco, State of California, have invented a new, original, and ornamental Design for a Book Match Packet, of which the following is a specification, reference being had to the accompanying drawing, forming part thereof.

Fig. 1 is a front elevational view of a book match packet showing my new design;

Fig. 2 is a side elevational view; and
Fig. 3 is a top plan view with the cover open as in Figs. 1 and 2.

The characteristic features of my design reside in the portions shown in solid lines.

I claim:

The ornamental design for a book match packet, substantially as shown and described.

GARNET J. WEIGEL.
